APPARATUS FOR TRANSPORTING
CONCRETE

Edward A. Hoffmann, Reading, Pa., assignor, by direct and mesne assignments, to Clinton Motors Corporation, Reading, Pa., a corporation of New York.

Application August 24, 1927. Serial No. 214,995

6 Claims. (Cl. 83—73)

This invention relates to a method of and apparatus for transporting concrete and has to do more particularly with large operations where, for practical purposes, it is desirable to mix 5 concrete at the central station and to thereupon transport it to different distinct localities for pouring or otherwise.

Large building operations of the present day have demonstrated that instead of mixing concrete on particular jobs where it is to be used, it is more economical to mix the concrete at a central station to which the constituent materials can be more easily and economically transported and after mixing the concrete to deliver 15 such concrete is mixed condition to the respective jobs or building operations. At the present time there are a few such central mixing plants where the concrete is mixed and thereupon transported to the respective jobs, but 20 numerous difficulties have arisen which threaten the practicability of these plants and up to the present time no satisfactory solution of the problem has been advanced.

For example, while it is highly economical to 25 mix concrete at a central station and transport it in mixed condition, it is found, in practice, that when mixed concrete is placed in a truck and transported for any appreciable distance, the constituents of the concrete will stratify in 30 accordance with their specific gravities by the time the truck has reached its destination, and in order to obtain a proper mixture of the mass, it is necessary to re-mix the concrete on the job 35 before pouring. In other words, it has been found that after concrete has been transported in a truck for a distance that the stone will settle to the bottom, and the sand, water and cement will stratify above the stone.

It is frequently necessary under present practice to employ men to board the truck with 40 shovels and shovel out the stone and gravel that accumulate in a closely compacted mass on the bottom of the truck. Pumping trucks are frequently employed in the transportation of 45 concrete, but even with such trucks shoveling generally has to be resorted to if the concrete is carried for any appreciable distance.

As a result of these facts, the concrete as it 50 leaves the truck and unless properly mixed, will not form a homogeneous masonry which its constituent parts or proportions should properly produce. For these reasons and others, careful builders are continuing to mix concrete from its 55 dry constituents on the respective jobs and con-

tiguous to the place where it is to be poured in spite of the higher cost of such operations.

I have exhaustively experimented in the handling of concrete for a prolonged period and, as a result of this exhaustive experimentation, I have found that the only way in which concrete can be mixed at a central station and delivered therefrom to respective building operations at distant localities, is to maintain a condition during transportation which will preclude stratification or 60 settling out of the constituents of the mixture.

I have discovered that if concrete is mixed in desired proportions and then transported in such a manner as to effect a continual agitation of the mass during transportation that the concrete 65 will reach such destination in as good a condition for pouring as it was when it left the central station. This constitutes the basis of the method of this invention which, generally stated, consists in producing an aqueous mixture of concrete at a 70 central station, thereafter loading it upon a vehicle, utilizing the vehicle to transport it to a distant station, maintaining the constituents of the mixture in continual agitation of the character to preclude settling or stratification and 75 discharging said mixed and agitated concrete from the vehicle at the place where it is to be used.

In practically carrying out the invention, I employ a vehicle having thereon a rotary cylinder mounted to rotate on a horizontal axis and 80 with which means is associated to constantly rotate the cylinder during transportation of the concrete. The concrete after being thoroughly mixed at a central station is deposited in the 85 rotary cylinder of the vehicle and while it is thus transported to the job or building operation, the cylinder is constantly revolved until the vehicle reaches its destination, there, by means of suitable hoisting mechanism associated with the vehicle, the cylinder is tilted to discharge the 90 contents thereof at a suitable point for pouring or otherwise, the cylinder being provided with an outlet or discharge gate through which the concrete may exit therefrom.

I find it highly practical to employ a motor 100 truck as a vehicle and to derive power for rotating and tilting the cylinder from the engine of the truck through suitable mechanical driving connections hereinafter more fully explained.

The present invention is directed not only to 105 the broad method to which I have referred, but also embodies structural features of truck construction hereinafter more fully explained and pointed out in the appended claims.

The accompanying drawings illustrate one form 110

of apparatus for carrying out the method of this invention, but the construction therein shown is to be understood as illustrative only and not as defining the limits of the invention.

5 Figure 1 is a side elevation of a portion of the truck embodying the present invention.

Figure 2 is a front elevation of the construction shown in Figure 1 with the chassis frame of the vehicle shown in section.

10 Figure 3 is a rear elevation of the construction shown in Figure 1;

Figure 4 is a diagrammatic view illustrating driving means for the controlling and tilting of the cylinder to discharge the contents thereof.

15 Referring to the drawings, 1 designates the chassis frame of a motor truck or other suitable vehicle. The running gear and driving connections for the truck chassis have not been shown as they may be conventional and any form of 20 motor truck may be employed without departing from the invention.

Mounted upon the frame 1 is a cradle 2 pivoted on a transverse axis 3 for tilting movement after the manner of a dump truck body. Mounted on the frame 1, at the forward end of the cradle 2, is a lifting apparatus 4, shown as a hydraulic lift. The lift embodies a cylinder 5 mounted on the truck and within each cylinder operates a piston 6 hydraulically controlled. The 30 top of the piston carries a yoke 7 at the outboard ends of which are mounted pulleys 8. Cables 9 are secured at one end of each of them to the chassis frame and extend upwardly over the pulleys 8 and thence downwardly and are secured to brackets 10 carried by the cradle, so that through operation of the hydraulic lift, the forward end of the cradle may be raised or lowered to tilt said cradle on the transverse shaft 3.

35 Supported near the front and rear ends of the cradle on suitable structural iron supports 11 or otherwise are two bearings 12 and on these bearings a hollow cylinder 14 is mounted to revolve. The bearings are braced by braces 13 to take up end thrust and to mount the cylinder so that it will rotate without appreciable end play or racking of its supports.

40 Supported near the front and rear ends of the cradle on suitable structural iron supports 11 or otherwise are two bearings 12 and on these bearings a hollow cylinder 14 is mounted to revolve. The bearings are braced by braces 13 to take up end thrust and to mount the cylinder so that it will rotate without appreciable end play or racking of its supports.

45 Trunnions 15 positioned coaxial with the cylinder and at opposite ends thereof are mounted in the bearings 12 and thus the cylinder is supported for rotation on its longitudinal axis.

50 At one point in the periphery of the cylinder, it is preferably provided with a filling opening adapted to be normally closed by a cover 16 maintained in closed position by fastening devices 17.

55 Moreover, the rear end of the cylinder is provided with a discharge opening positioned near the periphery of the cylinder and normally closed by a sliding gate 18. The gate has brackets 19 which are connected by links 20 to crank arms 21 on a rock shaft 22 (see Figure 3), and on the shaft is secured an operating handle 23 by which the cranks may be actuated to slide the gate 18 radially of the cylinder for the purpose of opening and closing the discharge opening.

60 It will be noted that with the crank arrangement shown the cranks 21 and links 20 function after the manner of a toggle which, when in the condition shown in Figure 1, will serve to lock the gate in closed position and preclude its inadvertent opening.

65 Encircling the cylinder is a ring gear 24 firmly affixed to the cylinder and this ring gear meshes with the pinion 25 mounted on a stub shaft 26. The stub shaft is connected by a universal joint 27 with a drive shaft 28. The forward end of

the drive shaft is squared at 29 and extends into a squared hole of a sleeve 30 into the opposite end of which extends the squared end 31 of a stub shaft 32 connected by a universal joint 33 to a power shaft 34. The squared ends of the shafts 28 and 32 are adapted for sliding movement within the sleeve 30 to compensate for slight longitudinal shifting of the shaft 28 when the cradle is tilted. In lieu of the squared ends, however, these shafts may be splined within the sleeve 30 or otherwise suitably connected for the same purpose as specified.

70 Mounted on the power shaft 34 is a gear or sprocket 35 driven by a gear or chain 36 from any suitable part of the motor of the truck 90 chassis. A clutch of any conventional form may be included in these connections, so as to render the rotation of the cylinder controllable by the driver of the truck.

75 It will be apparent from the description thus far advanced that after the concrete has been thoroughly mixed, it may be introduced into the filling opening by opening of the cover 16 and after introduction into the cylinder the truck may then leave for its destination. As soon as 100 the concrete is introduced, however, the cylinder is caused to revolve through the connections described and continues to revolve during the transportation of the concrete to its destination. When the truck reaches its destination, the rotation of the cylinder is discontinued and the hydraulic lift operated to tilt the cradle and thus 105 up-end the cylinder to a sufficient extent to cause the concrete to flow from the discharge opening when the gate 18 is opened.

80 I have found that during the pumping operation, careless drivers may forget to stop the operations of the hydraulic lift and in order to preclude damage to the truck through inattention of the operator in this regard, I have provided 115 automatic means for stopping the cylinder after it has been inclined at the desired maximum angle. This means is shown diagrammatically in Figure 4. Here the reference character 38 designates a conventional pump for supplying liquid 120 under pressure to the hydraulic lift. The pump is shown as having a drive pinion 39 driven from a gear 40 on a drive shaft 41. The drive shaft 41 is mounted for longitudinal reciprocation in suitable bearings (not shown) and is provided with 125 a gear 42 adapted, in the illustrative form shown, to mesh with the gear 43 which is the constant counter shaft gear of the transmission of the truck. 44 designates the transmission case. A handle 45 is connected to the shaft 41 and 130 through manipulation of the handles, the gear 42 may be thrown into and out of mesh with the gear 43 by sliding the shaft longitudinally, while the gear 40 remains at all times in mesh with the gear 39 of the pump.

85 A cable 46 is secured to the other end of the shaft through any suitable connection 47 and after passing over a pulley 48 is connected to the yoke 7 of the hydraulic lift.

Under normal conditions, the gear 42 is out 140 of mesh with the gear 43. However, when it is desired to dump the concrete, the handle 45 is moved in a clockwise direction in Figure 4 to move the gear 42 into mesh with the gear 43. The shaft 41 immediately commences to operate the pump 38 through the gearing connection shown and liquid is fed to the hydraulic lift to bring about the dumping operation. As the yoke 7 approaches the upper end of its maximum travel, it places the cable 46 under tension 145 150

and the continued upward movement of the yoke will draw the shaft 41 to the right in Figure 4 and disengage the gear 42 from the gear 43 before any damage can be done to the apparatus. 5 The structure shown in Figure 4 has been found to give very satisfactory practical results, but I wish it understood that this structure is for the purpose of illustration only and that changes may be made therein without departing from the 10 invention. It will further be understood that suitable valves are associated with the hydraulic lift to relieve the liquid when it is desired to lower the cradle to its horizontal position.

Actual practice has demonstrated that with 15 the mechanism which I have described, it is entirely feasible and practical to mix concrete at a central station and transport it for many miles to building operations without in anywise impairing the mixture or permitting stratification or 20 solidification thereof. Due to the constant rotation of the cylinder, there is a constant agitation of the mixture which effectually precludes the stratification or solidification and the concrete is thus delivered ready for use without 25 deterioration.

I wish to call particular attention to the fact 30 that the cylinder should be made water tight in order that none of the water embodied in the concrete mixture can escape during transportation, for if it were permitted to leak out, the consistency of the mixture would be altered during transportation.

It will be apparent that while the concrete is 35 being transported in the rotating cylinder, there is a continuous tumbling action occurring in the cylinder. This agitation of the mixture is such that there is no fixed top or bottom strata thereto, but, on the contrary, the relation of this different parts of the concrete will be constantly 40 changing.

My experience has shown that it is wholly practical to employ a cylinder which has a smooth, 45 unencumbered interior, and that concrete can be kept in proper condition by a cylinder so constituted and without the employment of rotary paddles, blades, etc. This is desirable as a smooth surface cylinder will discharge more efficiently and may be kept clean at all times.

The accompanying drawings show the invention 50 in its preferred practical form, but the invention is to be understood as fully commensurate with the appended claims.

Having thus fully described the invention, 55 what I claim as new and desire to secure by Letters Patent is:

1. In an apparatus of the character described, a truck embodying suitable drive mechanism in combination with a cylinder mounted on the truck for rotation on a normally substantially horizontal axis and for tilting movement, said cylinder having a smooth surfaced unencumbered interior provided with a charging opening having a suitable closure adapted to normally seal the opening, and means driven from the drive mechanism of the truck for imparting rotation to the cylinder after it has been charged and sealed.

2. In an apparatus of the character described, 70 a truck embodying suitable drive mechanism in combination with a cylinder mounted on the truck for rotation on a normally substantially horizontal axis and for tilting movement, said cylinder being provided with charging and dis-

charging openings having suitable closures adapted to normally seal the opening, and said cylinder being interiorly free of encumbrances and provided with a smooth unencumbered inner surface, means driven from the drive mechanism of the truck for imparting rotation to the cylinder after it has been charged and sealed, and means also driven from the drive mechanism of the truck for tilting the cylinder when desired to discharge the same through the discharging opening. 80

3. In an apparatus of the character described, a truck chassis embodying suitable propelling mechanism in combination with a cylinder mounted to rotate on the chassis and for tilting movement thereon, means for operatively connecting the cylinder to the propelling mechanism of the truck to rotate the cylinder for the purpose of precluding solidification or stratification of the contents thereof, operative connections between the cylinder and the propelling mechanism for tilting the former through power derived from the latter, and means controlled by movement of the former for automatically disconnecting the former from the latter after the cylinder has been tilted to a predetermined extent. 90

4. In an apparatus of the character described, a truck chassis embodying a suitable power plant in combination with a cradle mounted for pivotal movement on the chassis, a cylinder mounted on the cradle for rotation on a substantially horizontal axis, said cylinder being provided with a discharging opening normally sealed, means for operatively connecting the cylinder with the power plant of the chassis to rotate the cylinder while in sealed condition to preclude solidifying or stratification of the contents thereof, tilting mechanism mounted on the chassis and operatively connected to the cradle to tilt the cradle in a position to dump the contents of the cylinder when the discharging opening is unsealed, operating connections between the tilting mechanism and the power plant of the chassis to operate the tilting mechanism from said power plant, and means to automatically disconnect the tilting mechanism from the power plant after the cradle has been tilted to a predetermined maximum extent. 105

5. Apparatus of the class described, comprising an automotive truck having a body frame, a rotatable and tiltable tank having a smooth walled and unencumbered interior, carried by said truck and having its rear end substantially overlying the rear end of the body frame, a tiltable frame disposed between said tank and said body frame, a pivotal connection between said tiltable frame and the rear end of said body frame, a pair of longitudinally aligned trunnion bearings carried and supported by said tiltable frame, said tank having trunnions supported by said bearings, and means for rotating said tank. 120

6. Apparatus for transporting ready-mixed concrete from a mixing plant to a place of usage comprising, a vehicle, a tank on the vehicle mounted to rotate on a substantially horizontal axis, and means for giving a rolling over motion to the tank, the tank being without mixing blades and without an interior shaft along its axis of rotation, and the peripheral tank wall being substantially circular in planes at right angles to the axis of rotation of the tank. 135

EDWARD A. HOFFMANN.
